CLAIM

The ornamental design for a flowmeter transmitter circuitry housing, substantially as shown and described.

DESCRIPTION

FIG. 1 is a perspective view of a flowmeter transmitter circuitry housing embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; the side not shown is a mirror image of the side shown.
